Primary Examiner — Elizabeth J Oswecki(74) *Attorney, Agent, or Firm* — Fishman Stewart Yamaguchi PLLC(57) **CLAIM**

The ornamental design for an integrated circuit tag, as shown and described.

DESCRIPTION

FIG. 1 is a perspective view of an integrated circuit tag showing our new design;

FIG. 2 is a front elevational view thereof;

FIG. 3 is a right side elevational view thereof;

FIG. 4 is a left side elevational view thereof;

FIG. 5 is a top plan view thereof;

FIG. 6 is a bottom plan view thereof; and,

FIG. 7 is a cross sectional view thereof taken along the line 7-7 of FIG. 2.

The broken lines shown in the drawings represent portions of the integrated circuit tag that form no part of the claimed design. Dashed-dot-dashed broken lines define the boundaries of, but not included in, the claimed design.
